CUSHION SUPPORT FOR FURNITURE

Walter F. Herold, Bridgeport, Conn., assignor to
The Bassick Company, Bridgeport, Conn., a corporation of Connecticut

Application May 12, 1933, Serial No. 670,803

3 Claims. (Cl. 45—137)

The present invention relates to a cushion support for furniture, particularly for use with radio cabinets, phonograph cabinets and other structures in which vibrations are set up, an object being to provide a support which will absorb and damp such vibrations so that they will not be transmitted to the floor. Another object is to provide a support which will compensate for slight irregularities in the furniture, or in the floor, and which also has resiliency characteristics adapted to provide resilient, vibration absorbing, and compensating support for furniture of widely different weights.

A further object is to provide a cushion support in which a relatively large body of cushioning material is provided in exposed relation, and in which means is provided to confine such body against excessive lateral distortion, while at the same time maintaining the cushioning effect of the body in its most effective locale in relation to the supported weight.

Another object is to provide a cushion support having a resilient body and a hard floor engaging shoe, and in which means is provided for maintaining the body against uneven distortion and displacement.

With the above and other objects in view an embodiment of the invention is shown in the accompanying drawing, and this embodiment will be hereinafter more fully described with reference thereto, and the invention will be finally pointed out in the claims.

In the drawing:

Fig. 1 is a side elevation of a cushion support, according to the illustrated exemplary embodiment of the invention.

Fig. 2 is a top plan view thereof.

Fig. 3 is a vertical sectional view.

Fig. 4 is a vertical sectional view with a furniture leg supported in the device, and showing the relative arrangement of the parts under load.

Fig. 5 is a side elevation of the cushion body.

Fig. 6 is a bottom plan view thereof.

Fig. 7 is a plan view of the resilient retaining ring employed.

Fig. 8 is a sectional view of the metal floor engaging shoe.

Similar reference characters indicate corresponding parts throughout the several figures of the drawing.

Referring to the drawing, the cushion support, according to the exemplary illustrated embodiment of the invention, comprises a circular cushion body 10, formed of rubber or other

suitable resilient material, its upper portion, which is adapted to be exposed, being in the form of a truncated cone and its lower portion, which is adapted to be retained and confined within the floor engaging shoe, being in the form of a relatively flat inverted truncated cone, there being an annular groove 11 in the side wall between these upper and lower portions. Another annular groove 12 is provided in the side wall intermediate the upper and lower ends of the upper portion, for the reception of a spring-ring confining member, presently to be more fully referred to, and the upper surface is provided with a concavity 13 in which the end of the furniture is adapted to rest. The under surface of the cushion body is provided with a series of spaced concentric ribs 14, the resilient cushioning action of which will be presently more fully explained.

The floor engaging shoe or the base 15 is provided with an upwardly and inwardly curved rim 16 into which the lower portion of the cushion body is adapted to be forced and expanded, the edge of the rim 16 engaging the annular groove 11 to thus interlockingly retain the parts together. A relatively stiff resilient split-spring ring 17 is engaged in the groove 12, after the body is inserted in the shoe, and prevents removal of the cushion body as long as the ring remains in place, the ring providing a uniform confining reinforcement about the body which prevents its distortion at any one point, distributing strains thereon uniformly about the body. As such distortion is necessary to insert and remove the body it will be seen that the ring effectually retains it, while at the same time preventing such distortion as might result from an uneven load imposed on the support or side pressure set up through sliding the furniture. The spring ring furthermore confines the relatively large exposed area of the cushion body against excessive lateral distortion, so that the effective cushioning action of the support is properly directed beneath the supported load. In order to prevent cutting of the cushion body under extremely heavy loads and also provide a cushioning support for such heavy loads the split spring ring has expansibility under such heavy loads thus permitting limited lateral distortion of the cushion body while preventing excessive lateral distortion.

The shoe 15 is slightly dished so that a space is provided between its surface and the flat under surface of the cushion body, so that the body is supported in the manner of a bridge by

the shoe and has a limited flexing under very light loads between its flat position and the position where the under surface engages and conforms to the shoe. Also an annular space 5 is provided between the inclined side wall of the lower portion of the body and the inner surface of the rim 16 of the shoe, and which permits of outward expansion of the body under load. The reduced cross-sectional area of the lower ribbed portion 14 and the air spaces 10 between the ribs is such that this portion will compress to a substantial degree under moderately light loads, while heavy loads will cause compression in the main rubber body. In any case a proper cushion support adapted to absorb 15 and damp vibrations is provided for practically any of the usual weights of radio and phonograph cabinets.

I have illustrated and described a preferred 20 and satisfactory embodiment of the invention, but it will be obvious that changes may be made therein, within the spirit and scope thereof, as defined in the appended claims.

Having thus described my invention what I 25 claim and desire to secure by Letters Patent is:—

1. A cushion support for furniture, comprising a floor engaging shoe, a cushion body of resilient material including a lower portion disposed and retained in said shoe and an upper portion disposed above said shoe, and a confining split 30 spring ring disposed about said body at a point above said shoe having a lesser degree of resiliency than the material of said cushion body, the outer peripheral surface of said ring being unconfined and said ring having lateral expansibility to prevent excessive lateral distortion of said cushion body while permitting limited lateral distortion of said cushion body under predetermined loads.

2. A cushion support for furniture, comprising a floor engaging shoe, a cushion body of resilient material including a lower portion disposed and retained in said shoe and an upper portion disposed above said shoe, there being an annular groove in the side wall of said body above said shoe, and a confining split spring ring disposed in said groove having a lesser degree of resiliency than the material of said cushion body, said groove confining the inner peripheral surface and the upper and lower surfaces of said ring, the outer peripheral surface of said ring being unconfined and said ring having lateral expansibility to prevent excessive lateral distortion of said cushion body while permitting limited lateral distortion of said cushion body under predetermined loads. 80 85 90

3. A cushion support for furniture, comprising a floor engaging shoe having a side wall and an inwardly extending flange at its upper edge, a cushion body of resilient material including a lower portion disposed in said shoe and an upper portion disposed above said shoe, there being an annular groove between said lower and upper portions engaged by said flange of the shoe, 95 and there being an annular groove in the side wall of said body above said shoe, and a confining split spring ring disposed in said second groove having a lesser degree of resiliency than the material of said cushion body, said groove 100 confining the inner peripheral surface and the upper and lower surfaces of said ring, the outer peripheral surface of said ring being unconfined and said ring having lateral expansibility to prevent excessive lateral distortion of said 105 cushion body while permitting limited lateral distortion of said cushion body under predetermined loads. 110 115
